DONALD B. KNIGHT, OF BROOKLYN, NEW YORK

REFRIGERATION

Application filed May 24, 1928. Serial No. 280,139.

REISSUED

This invention relates to the system of refrigeration described in Letters Patent of the United States No. 1,609,334, dated December 7, 1926. In that system, as disclosed in said Letters Patent, the development of internal pressure is a necessary incident. This requires the apparatus to be so constructed as to be capable of resisting such pressure, with consequent expense. It also subjects the apparatus to restrictions imposed by local communities and to regulations of the Interstate Commerce Commission governing the use and shipment of compressed gases. It creates sales resistance due to fancied or real dangers attending the use of gases under compression. It requires careful tests to insure reasonable safety. It involves service cost due to leakage. It requires expenditure of time and labor in charging the apparatus and in purging it. It is the object of the present invention to enable refrigeration by methods of the general character of that described in said Letters Patent to be carried on at atmospheric pressure, without the development of internal pressure of material degree in any part of the apparatus and without subjection to such objections as have been described above.

In accordance with the invention the cooling agent employed is of relatively low vapor pressure and is evaporated in the presence of an inert auxiliary agent at atmospheric pressure, the circulation of the auxiliary agent being accomplished also under substantially atmospheric pressure, by difference in specific weights of vertically extending bodies of fluid in the system. It will be seen that the invention is characterized by the employment of a cooling agent of relatively low vapor pressure, such, for example, as a solution of phenol or kerosene and ether and an auxiliary agent, such, for example, as nitrogen or atmospheric air into which and in the presence of which the ether diffuses and evaporates, all under atmospheric pressure.

In the practice of the invention the following conditions should be established. The refrigerating fluid should be condensable at atmospheric pressure at a temperature, such as normal room temperature, easily reached with the available cooling water or other con-

densing means. The auxiliary agent should be gas lighter per unit volume than the vapor of the refrigerating fluid and chemically inert to it. The absorption medium should be such that at atmospheric pressure it will absorb the vapor of the refrigerating fluid even though it is greatly diluted by the auxiliary fluid, it being apparent that if the auxiliary agent has a great effect upon the ability of the refrigerating fluid to evaporate in the evaporator, it will have the same tendency in the absorber. The auxiliary agent should be present in large volume in order that a sufficiently low evaporating temperature may be attained with a liquid of relatively high boiling point, the vapor of the refrigerating fluid being, therefore, very dilute in the auxiliary agent and requiring a powerful absorbent fluid for its removal. The process must be carried on in such manner that the refrigerating fluid will be evaporated in sufficient quantity to realize a practical amount of refrigeration.

It will be noted here that it is characteristic of liquids which boil at temperature slightly above ordinary or normal room temperature, at substantially atmospheric pressure, that as the conditions are reached under which such liquids will evaporate at freezing temperatures, they must be very much expanded or exceedingly dilute in the auxiliary agent. A large quantity of the auxiliary agent must therefore be circulated for a comparatively small amount of refrigeration. The circulation of the relatively heavier refrigerating fluid is dependent primarily upon the evaporation of that fluid and the method of evaporation is therefore of great importance. The design of the evaporator is therefore of importance, particularly with a view to the prevention of the formation of a protective blanket of vapor which would tend to prevent the auxiliary agent from performing its function. As will be seen hereinafter, the evaporator shown and described herein has been designed to meet this condition.

The invention will be more fully explained with reference to the accompanying drawings in which it is illustrated and in which:

Figure 1 is a somewhat diagrammatic view,

in sectional elevation, showing a form of apparatus adapted for the practice of the invention.

Figure 2 is a detail view showing the construction and arrangement of the refrigerating chamber as seen from above, with the top removed.

Figure 3 is a detail view in perspective illustrating particularly the connection of 10 one of the trays of the refrigerating chamber to the ice chamber.

Figure 4 is a detail view in perspective of 15 one of the asbestos sheets which forms the bottom of one of the trays of the refrigerating chamber as seen from below, with its frame.

Figure 5 is a detail view illustrating the 20 construction and arrangement of the refrigerating chamber, ice chamber and trays, as seen from the left-hand in Figure 1 with the end wall removed.

Figure 6 is a detail view illustrating the arrangement of the trays in the absorber.

Figure 7 is a fragmentary view showing 25 the application of cooling water pipes to the trays in the absorber.

The cooling agent, which for purposes of explanation of the nature of the invention and by way of example only, may be taken 30 to be a solution of phenol or kerosene and ether may be introduced into the apparatus through a filling plug conveniently located, as at *k*, in a generator, as at *K*, and the auxiliary agent, which may also be taken for purposes of explanation and by way of example only, to be nitrogen or atmospheric air, may be introduced into the apparatus at any convenient point as through the vent pipe *a* which at its open upper end terminates 35 above the rest of the apparatus. By a suitable source of heat, indicated at 14, the cooling agent is heated and is caused to rise through a pipe 11 to the upper part of a condenser or separator *K*¹ which is independent of the generator *K* and in which the 40 vapor of the heated cooling agent is separated from the absorption liquor, such as phenol or kerosene, for example, which is in solution with the ether or its functional equivalent. From the separator *K*¹ the vapor of 45 the cooling agent passes upward through the pipe 11¹ which may include at *E* a rectifier or air condenser by which any vapor of the absorption liquid which may have been carried upward with the vapor of the cooling agent is condensed and separated to be returned to the separator *K*¹.

Substantially at the highest point of the apparatus the vapor enters a condenser *C* 50 within which is a pipe *B* suitably connected to a continuous supply of cooling water.

The condensed vapor, which is rich in ether or its equivalent, is conducted from the condenser *C* through the pipe 12 to the evaporator *G* which is placed within the refrigerat-

ing chamber, indicated at *G*¹. The preferred construction of the evaporator will be described more fully hereinafter. For present purposes it will be sufficient to say that the construction of the evaporator is such that the evaporation of the cooling agent proceeds rapidly in the presence of the auxiliary agent, such as air or nitrogen, with consequent absorption of heat and refrigeration.

From the evaporator the vapor passes by reason of its own specific gravity downward through the pipe *M* and its extension *M*¹ to the lower part of the absorber *A*, the pipe *M* preferably enclosing an inner pipe *N*, through which the relatively lighter auxiliary agent passes upward from the upper part of the absorber *A* to the upper part of the evaporator *G*, the described relation of pipes *M* and *N* forming a heat exchanger by means of which the desired circulation of the vapor of the cooling agent and the auxiliary agent between the evaporator *G* and the absorber *A* is promoted.

Within the absorber *A* the solution of the cooling agent and the absorption liquor takes place, the construction of the absorber, as will be explained more fully hereinafter, being such that the concentration of the solution progresses.

The absorption liquor is delivered to the absorber *A* from the separator *K*¹ through the pipe *P* connected to the separator *K*¹ near its lower end, a heat exchanger *T*, and a precooler *X*, from which the absorption liquor, poor in cooling agent, is delivered through the pipe *P*¹ to the upper part of the absorber *A*, passing by gravity to the lower part of the absorber and becoming progressively concentrated. It will be observed not only that the absorption liquor is mostly concentrated in the lower part of the absorber *A*, but that the vapor of the cooling agent from the evaporator *G* attains its highest strength as it reaches the lower part of the absorber *A*.

From the absorber *A* the concentrated solution passes through a pipe *L*, the external portion of the heat exchanger *T*, and the pipe extension *L*¹ back to the generator *K* where the cycle begins its repetition. The pipe *L* is preferably extended upward with the absorber for a short distance as represented in the drawing in order that the concentrated liquor may accumulate to a moderate depth in the absorber, the absorption of the cooling agent, in its richest condition, being carried on at the surface of the liquor in the lower part of the absorber.

It being one purpose of the present invention to permit the refrigeration to be carried on at substantially atmospheric pressure, connection from the absorber to the atmosphere is established through the vent pipe *a*, the open upper end of which, as previously

stated, terminates above the rest of the apparatus.

To equalize the pressure in the several parts of the apparatus, to prevent the building up of pressure on the generator side, and to permit the escape of air which may be carried over with the vapor from the generator, a direct vapor connection between the vapor space of the condenser C and the evaporator is established through a pipe c.

It being very desirable that evaporation of the cooling agent shall proceed as rapidly as possible in the evaporator, the construction of the evaporator shown in Figures 2, 3, 4 and 5 is preferred. As shown particularly in Figure 2, the evaporator is formed with two wings or parts G² and G³ which are substantially identical in construction and receive between them the ice chamber H in which ice may be formed if desired. Each part or wing comprises a series of horizontal trays g which may be secured by solder or otherwise to the walls of the ice chamber H. Each tray is formed with a lower flange g¹ and with a series of relatively large openings g², which are closed from the underside by a sheet g³ of asbestos or other suitable material, secured to the underside of the tray by a light frame g⁴, which may be secured to the tray in any convenient manner, as by bolts at g⁵. The cooling agent is delivered by a branch 12^a or 12^b to the uppermost tray of each series and, through the openings g², saturates the asbestos sheet from the underside of which evaporation of the cooling agent proceeds rapidly, without the formation of a protecting blanket, the vapor thus disengaged at atmospheric pressure passing down through the pipes N to the absorber, as already explained. The absorber is so constructed as to promote absorption by the absorption liquor of the cooling agent at the surface of the liquor. Accordingly it is provided interiorly with a series of horizontal trays a¹, a², a³, each of which is provided, as at a⁴, with an outlet which is raised slightly above the bottom of the tray so as to permit accumulation of the absorption liquor to a moderate depth. The outlets a⁴ are staggered so that the liquor flows over the whole surface of the trays, exposing a large surface for absorption of the auxiliary agent within the absorber. As the absorption liquor passes from one tray to the next below it and eventually to the bottom of the absorber vessel the liquor becomes more and more concentrated until it is in readiness to be returned to the generator. For the purpose of cooling the absorber and the absorption liquor during the process of absorption a cooling water pipe o, connected to a suitable supply, is introduced into the absorber at a convenient point, and is soldered to the underside of each tray a¹, a², a³, with many turns, and is eventually led from

the absorber A, as at o¹, passing through the pre-cooler and discharging as at o².

In operation it will be understood that when heat is applied to the generator K the solution is raised from the generator into the separator K¹ the ether or other cooling agent being at the same time separated from the absorption liquor, such vapor, being freed as far as possible from the trays of absorption liquor, being then conducted to the condenser C where the vapor is condensed into liquid form and passes on through the evaporator G, such condensed liquid being practically pure ether or whatever other cooling agent may be employed. The liquid ether is distributed over the trays of the evaporator in the presence of the auxiliary agent, such as air or nitrogen or other suitable agent which is non-condensable at the temperature at which it operates and is inert with respect to the other chemical substances within the apparatus. In the presence of such auxiliary agent the ether or other cooling agent diffuses and evaporates into the auxiliary agent, heat being thereby abstracted from the surroundings while no change in actual or total pressure as between the condenser and the evaporator is necessitated.

It will be observed that either nitrogen or air or some functionally equivalent agent may be employed advantageously with ether as the cooling agent. Because such an auxiliary agent and such a cooling agent have specific and molecular weights which differ greatly with the result it is possible to obtain efficient circulation and efficient diffusion.

The ether vapor and auxiliary agent mingle in the evaporator and flow downwardly into the lower part of the absorber A where the gaseous mixture comes in contact with the weak absorption liquor supplied thereto from the separator K¹, that is with the liquor in which there is dissolved a relatively less amount of the cooling agent, such liquor being preferably pre-cooled before it enters the absorber.

Through the established relation of the gaseous mixture and the absorption liquor there results an absorption or dissolving of the ether by the absorption liquor and a liberation of the auxiliary agent. Since the auxiliary agent is of markedly different specific weight than the cooling agent and is very much lighter than the cooling agent, it will be seen that the weight per unit volume of gas after it is freed from the ether or other cooling agent in the absorber is less than the weight per unit volume of the gaseous mixture in the evaporator. As a result there will be a constant circulation of fluids between the absorber and the evaporator.

In the operation as thus described the head under which the movement takes place is produced rather by difference in the degree of the mixture than by absolute separation

of the elements and subsequent admixture. Some of the ether and other cooling agent passes upward through the pipe M from the absorber along with the auxiliary agent to the evaporator, but the amount of cooling agent thus entrained is small relatively to the proportion of the cooling agent in the mixture within the evaporator.

Absorption liquor, saturated with the cooling agent, is carried from the absorber into the generator K under the influence of the heat applied to the generator. As vapor is formed within the generator it pockets some of the absorption liquor while it is escaping through the conduit 11 and such bodies of liquor will thereby be lifted into the upper part of the separator K¹. The liquor thus displaced in the generator K is replaced by additional strong liquor from the absorber, while the weaker liquor, which has been separated in the separator K¹ runs by gravity back into the absorber.

It will be seen that while the actual or total pressure in the apparatus remains at substantially atmospheric pressure, there is a variation as between actual pressures in the evaporator and absorber, the sum of which is equal to the actual or total pressure.

It will further be understood that as the apparatus functions at substantially atmospheric pressure the partial or differential pressures of the cooling agent and the auxiliary agent are respectively below atmospheric pressure and that the lower the pressure of the cooling agent becomes the lower will be the temperature at which it will evaporate, the presence of the auxiliary agent not only permitting operation at constant total pressure, but if present in sufficient quantity to exert sufficient partial pressure the cooling agent exerts a partial pressure low enough to permit it to evaporate at freezing temperatures. Thus the auxiliary agent permits operation at a uniform total pressure and operation at substantially atmospheric pressure, such atmospheric pressure being dependent to some extent upon the amount of auxiliary agent present.

It will be observed that the operation of the system embodies the circulation of the cooling agent from the generator, through the condenser, through the evaporator, through the absorber and back to the generator; a local circulation of the auxiliary agent between the evaporator and the absorber; and a local circulation of the absorption liquor between the generator and the absorber.

I claim as my invention:

1. The process of refrigerating which comprises evaporating a liquid cooling agent of relatively low vapor pressure in the presence of an auxiliary agent inert to the cooling agent at substantially atmospheric pressure, producing a head due to difference in specific weights of a mixture of the vapor of

the cooling agent and the auxiliary agent on the one hand and the auxiliary agent on the other hand, forcing the mixture of the vapor of the cooling agent and the auxiliary agent under the influence of the head produced into the presence of an absorption liquor at substantially atmospheric pressure, absorbing the cooling agent in the absorption liquor, withdrawing the absorption liquor from the presence of the auxiliary agent, returning the auxiliary agent into the presence of the cooling agent under the influence of the head produced, heating the absorption liquor and expelling the cooling agent from solution, returning the absorption liquor into the presence of the mixture, condensing the cooling agent at substantially atmospheric pressure, and returning the condensed cooling agent into the presence of the auxiliary agent.

2. The process of refrigerating which comprises evaporating a liquid cooling agent of relatively low vapor pressure in the presence of an auxiliary agent inert to the cooling agent and at substantially atmospheric pressure and having a specific weight lower than the specific weight of the vapor of the cooling agent, producing a head due to difference in specific weights, forcing the mixture of the vapor of the cooling agent and auxiliary agent under the influence of the head produced into the presence of an absorption liquor at substantially atmospheric pressure, segregating the cooling agent from the auxiliary agent by absorption, and returning the auxiliary agent into the presence of the cooling agent under the influence of the head produced.

3. The improvement in the process of refrigerating by the aid of a system including an evaporator and an absorber which consists in diffusing a cooling agent of relatively low vapor pressure in the presence of an auxiliary agent in the evaporator at substantially atmospheric pressure, and circulating under substantially atmospheric pressure the auxiliary agent through the evaporator and the absorber exclusively by difference in specific weights of vertically extending bodies of fluid in the system.

This specification signed this 22nd day of May, A. D. 1928.

DONALD B. KNIGHT.
